UNITED STATES PATENT OFFICE

FREDERICK E. ROBINSON, OF CLEVELAND, OHIO, ASSIGNOR TO THE ROTAWASHER CORPORATION, OF CLEVELAND, OHIO, A CORPORATION OF OHIO

REMOTE-CONTROL SWITCH FOR PUMPING SYSTEMS

Application filed June 23, 1928. Serial No. 287,875.

This invention relates to a combined valve and electric switch enabling the closing or opening of a conduit for fluid concurrently with the closing or opening of a switch controlling an electric motor operating a pump for forcing liquid through such conduit. An illustration of such a hydraulic system is found in a machine for washing motor cars, trucks and other vehicles, such machine comprising a motor, a pump driven thereby, a hose and nozzle supplied by the pump and suitable controls for the water conduit and motor.

It is the object of my invention to supply in a very simple and efficient form, a shut-off valve associated with a push button switch, so combined, that the opening of the valve results in the operation of the push button to cause the closing of the motor circuit to operate the pump, while the closing of the valve to shut off the water results in the push button being freed to cause the opening of the motor circuit. Although the valve and switch operate concurrently, it is preferable that the valve be somewhat open before the motor circuit is closed, and that the motor circuit be open before the valve is entirely closed, so that there will be no danger of the motor attempting to drive the pump when the latter has no outlet, thereby straining the motor.

A feature of my invention is that it employs a standard valve and a standard push button control. With these I have incorporated very simple parts which cause the automatic conjoint operation stated.

In the drawings, Fig. 1 is a diagrammatic view of a washing system involving my invention; Fig. 2 is an enlarged elevation partly sectional of the valve and push button control; Fig. 3 is a perspective illustrating the push-button switch and my attachment therefor; Fig. 4 is a longitudinal section through the valve and push button control at right angles to Fig. 2, as indicated by the line 4-4 on that figure; Fig. 5 is a cross-section through the push button control as indicated by the line 5-5 on Fig. 4.

Referring first to Fig. 1, A indicates a pump, B a feed pipe leading thereto, C the

discharge line therefrom, D a valve in such pipe, E the line from the valve, F a discharge hose leading from such line, and G a discharge nozzle on the end of the hose. H indicates the driving motor which is suitably connected with the pump A. This motor is shown as controlled by a solenoid starting switch J, which may have a solenoid magnet j, a switch arm j1, and various contacts with resistance as indicated at j2. K indicates the push button control, generally. Suitable circuits L lead from this control to the solenoid switch, the motor and one of the supply lines, while circuits M lead from the solenoid switch to the motor and the other supply line.

Frequently on the discharge line from the pump there will be several valves D controlling corresponding discharge hose and nozzles. Associated with each of such valves will be a corresponding push button control K. It is not deemed necessary to show the installation in multiple, as that will be understood, and as my invention relates particularly to the combination illustrated of the valve and push button control. Such feature will now be described, with reference particularly to Figs. 2 to 5 inclusive.

As shown in Fig. 4, each valve D comprises a casing having the usual tapered plug 10, with an opening 11 through it. A suitable handle 12 mounted on the stem of this plug is adapted to give it a quarter turn from the entirely open position shown in Fig. 4, and in full lines in Fig. 2, to the closed position indicated by broken lines in Fig. 2.

The push button control K may comprise a suitable box 20 containing an insulating block 21 (Fig. 2) on which are mounted a pair of contacts 22 and 23 constituting terminals of the two lines L. The insulating block 21 is shown as carrying a cross bar 25 in which is slidably mounted a stem 26 carrying a metallic cross head 27 adapted to bridge across the two contacts 22 and 23. On the end of the stem is a suitable head 28, within which is a compression spring 29 bearing against the plate 25 and tending to push the button outwardly to maintain the contacts open. The switch box has a cover

plate 24 with an opening through which the push button head freely projects. The cross head 27 is preferably somewhat loosely mounted on the stem 26 so that it may always be able to make a good contact with both contacts 22 and 23, notwithstanding wear. A small spring 27a mounted in a cup 27b on the stem normally presses the cross head inwardly toward an insulating stop 27c on the stem. This stop pulls the cross head entirely free from the contacts when the spring 29 acts to push the head 28 outwardly.

Such a push button switch as just described is on the market intended for manual operation to control a circuit as desired. To combine such push button with the valve, I provide the mechanism now to be described.

I mount on the cover plate 24 of the push button switch, a flexible strip 30 extending lengthwise of the switch box and engaging the face of the push button. This flexible strip may comprise one or more surmounting steel ribbons which may be secured in place by screws 31. The same screws may be used to secure the strip to the cover and the cover to the box 20, as shown in Fig. 2. I secure to the side of the box K a suitable stirrup 35 which may embrace the discharge pipe E and hold the box in place. The stirrup is shown as secured by screws 36 passing into the side wall 20 of the box.

Positioned in the same longitudinal plane with the ribbon 30, is a suitable cam 40 rigid with the valve plug. I find it convenient to make this cam in the form of an extension of the plug handle 12, and such is the form shown in Fig. 4, although, if desired, the cam may be a separate member rigidly secured to either the handle or the plug of the valve.

In the normal closing position of the valve, as indicated by broken lines in Fig. 2, the cam 40 is entirely free from the ribbon 30 and the spring 29 maintains the push button in its outermost position so that the electric circuit to the pump is open. Now, when the handle 12 is swung toward opening position, the plug 11 partially opens the conduit before the cam 40 comes into active engagement with the ribbon 30, then as the handle is turned to its final open position, the cam presses inwardly on this ribbon and slides along it until the cam comes into the position shown in Fig. 2, directly opposite the push button, where it holds the push button in its closed position, starting the motor.

Whenever it is desired to shut off the water, the handle is swung from the open position shown in Fig. 2, toward the dotted line position. The first action of such movement is to release the push button so that the current to the motor is broken, and thereafter, as the handle comes into its final transverse position, the valve is entirely closed.

It will be noticed that the box 20 extends

from the push button farther in one direction than the other. This is a customary form as it enables the same box to be used for a double push button, simply the original parts and a new cover plate being used when it has but one push button. A longer box however is advantageous in my operation, because the longer strip 30 requires a less bending moment within the strip. The strips shown are considerably exaggerated in thickness in the drawing for clearness of illustration. In practice, I find it satisfactory to make these strips of about five thousandths or six thousandths of an inch in thickness, and I prefer to use two surmounting strips and secure the inner one tightly only at one end, leaving it slidably guided at the other end.

It will be observed that, on the installation shown, that there is no valve on the nozzle itself, and accordingly it is necessary for each operator when he is through using the water to shut it off at the corresponding valve D, and such action operates the control which would shut off the motor as far as he is concerned. In a multiple installation, whether the motor is actually shut off depends on whether the other valves are opened or closed, as it would require the closing of all the valves to shut off the motor, although the opening of any one would be sufficient to start the motor.

I claim:

1. The combination of a push button controlling device, a flexible strip overlying the push button, and a cam adapted to engage and slide along the strip to operate the push button.

2. The combination of a push button controlling device, a flexible strip overlying the push button, an adjacent valve, and a cam movable with the valve and adapted to engage the strip to operate the push button.

3. The combination of a control box having suitable terminals, a push button adapted when pushed inwardly to connect said terminals, a spring tending to push the button outwardly, a cover for the box, a flexible metal strip secured to the cover and overlying the push button and adapted to be pushed outwardly by said spring, and means to engage the strip and push it inwardly to operate the push button.

4. In a cam operated push button switch, a flexible strip adapted to be secured at its extremities to the face of a switch housing, one side of said strip being in contact with the push button, whereby the switch may be operated by a cam exerting force upon said strip.

5. In a cam operated push button switch, a plurality of resilient strips lying in juxtaposition to each other, one of said strips being adapted to be secured at its extremities to the face of the switch housing, and the

remainder of said strips being adapted to be secured at one extremity only to said housing, said strips overlying the push button, whereby a force exerted upon the strips will operate the switch.

5 6. The combination of a control box having suitable terminals, a push button adapted when pushed inwardly to connect said terminals, a spring tending to push the button outwardly, a cover for the box, a plurality of metal strips, overlying the push button and adapted to be pushed outwardly by said spring, the outside strip being secured at both extremities to said cover, the remaining strips 10 being secured at one extremity only, and means to engage said strips and push them inwardly to operate said push button.

15 In testimony whereof, I hereunto affix my signature.
